UNITED STATES PATENT OFFICE.

ALVA THOMAS HAYNES, OF WHEATLAND, CALIFORNIA.

MOWING-MACHINE.

SPECIFICATION forming part of Letters Patent No. 738,033, dated September 1, 1903.

Application filed November 7, 1901. Serial No. 81,516. (No model.)

To all whom it may concern:

Be it known that I, ALVA THOMAS HAYNES, a citizen of the United States, residing in Wheatland, in the county of Yuba, State of California, have invented a new and useful Mowing-Machine, of which the following is a specification.

My invention relates to improvements in mowing-machines, particularly with reference to the cutting apparatus; and it consists in the peculiar construction and combination of devices hereinafter fully set forth and claimed.

In the accompanying drawings, Figure 1 is a top plan view of a mowing-machine cutting apparatus embodying my improvements, the hangers in which the power-shaft is journaled being shown in section. Fig. 2 is a detail top plan view. Fig. 3 is a vertical transverse sectional view. Fig. 4 is an end elevation looking in the direction of the arrow x. Fig. 5 is a longitudinal sectional view taken on the line 5 5 of Fig. 1 and looking in the direction of the arrow thereon.

In the embodiment of my invention I provide a sickle-bar 1, the inner end of which is attached to a shoe 7 by means of bolts 10. The said shoe is preferably of the form shown and is provided on its inner side with a shield 17. The latter curves upwardly at its front end and at its outer side. The shoe 7 is provided on its upper side with a pair of standards 9, which project inwardly and upwardly therefrom and are provided at their inner ends with bearings for a shaft 13. The latter rotates directly in hangers 12, which are clamped in the said bearings by means of set-screws 14, and the said hangers form the connection between the cutting apparatus and the mowing-machine frame. The latter is not shown, as it forms no part of my present improvements. At the outer end of the sickle-bar 1 is a dividing-guard 8, which also forms a shoe or runner. It will be understood from the foregoing description and by reference to Fig. 1 of the drawings that the standards 9, shaft 13, and hangers 12 form a pivotal connection between the mowing-machine frame and the cutting apparatus on the sickle-bar 1, which admits of the raising and lowering of the cutting apparatus. The shaft 13 is provided with a sprocket-wheel 15, whereby

power is applied thereto and said shaft rotated, and the said shaft is further provided with a pair of eccentrics.

55

To the under side of the finger-bar 1 is secured a guide-bar 3, which projects forwardly therefrom and is provided in its upper side with a longitudinal guide-groove 3^a. The lower cutter-bar 6 bears on the said guide-bar 3 and against the front side of the finger-bar 1 and is provided on its under side with a longitudinal guide-flange 6^a, which operates in the guide-groove 3^a. The upper cutter-bar 5 bears upon the lower cutter-bar 6 and against the front side of the finger-bar 1 and has a longitudinal guide-flange 5^a on its upper side at its rear edge.

65

A plate 2 forms a housing or cover for the upper cutter-bar, is provided on its under side with a guide-groove 2^a, in which the guide-flange 5^a operates, and is further provided with openings 18 for the admission of lubricant, as shown. The finger-bar 1 is provided on its upper side with hinge members 1^a, and the plate or housing 2 is provided at its rear side with similar hinge members 4, and pin-tiles 4^a being inserted in registering openings with which the said hinge members 1^a 4 are provided. The housing-plate 2 is hinged on the finger-bar, so that the same may be raised to uncover the cutter-bar and permit the latter to be removed for the purpose of sharpening them or for other purposes. The said housing-plate is shown disposed in an elevated position in dotted lines in Fig. 2.

100

When the housing-plate is in its operative position shown in the drawings, the same is firmly secured on the finger-bar 1 and in position to bear upon the upper cutter-bar 5 by screws 11, which also serve to adjust the said housing-plate to compensate for wear, as hereinbefore described. The inner ends of the upper and lower cutter-plates are respectively connected to the eccentrics 13^a of the shaft 13 by means of pitmen 16. It will be understood that when the shaft 13 is rotated the upper and lower cutter-plates will be reciprocated and will move simultaneously in opposite directions.

Having described my invention, I claim—

1. In a mowing-machine, the combination with a shoe, of standards rigid therewith, hangers secured within the standards, a

power-shaft carrying eccentrics and having its terminals journaled in the hangers, said hangers forming the means of attachment to the frame of a machine, and the shaft forming a pivot for the shoe, a finger-bar secured to and carried by the shoe and having a guide, a lower cutter-bar engaging the guide, an upper cutter-bar, a housing hinged to the finger-bar and constituting a guide for the upper cutter-bar, and pitmen connecting the cutter-bars and the eccentrics, substantially as described.

2. In a mowing-machine, the combination with a shoe, of standards rigid therewith, hangers secured in the standards, a shaft having its terminals housed within the hangers and carrying eccentrics, said hangers con-

stituting the means of attachment to the machine-frame and the shaft forming a pivot for the shoe, a finger-bar secured to the shoe ²⁰ and having a guide, a lower cutter-bar engaging the guide, an upper cutter-bar, a housing hinged to the finger-bar and constituting a guide for the upper cutter-bar, adjusting-screws to secure the housing to the finger-bar, ²⁵ pitmen connecting the cutter-bars and the eccentrics.

In testimony whereof I have signed my name to this specification in the presence of two subscribing witnesses.

ALVA THOMAS HAYNES.
